UNITED STATES PATENT OFFICE.

JOSEPH ROSS, OF NEW YORK, N. Y., ASSIGNOR TO HENRY J. GAISMAN AND FERDINAND S. M. BLUN, OF SAME PLACE.

DESIGN FOR A BELT-BODY.

SPECIFICATION forming part of Design No. 34,048, dated February 5, 1901.

Application filed July 26, 1900. Serial No. 24,948. Term of patent 7 years.

To all whom it may concern:

Be it known that I, JOSEPH ROSS, a citizen of the United States, residing in New York city, borough of Manhattan, State of New York, have invented and produced a new and original Design for a Belt-Body, of which the following is a specification, reference being had to the accompanying drawing, forming part thereof, which is a face view of a body portion of a belt embodying my design.

As shown in the drawing, the leading or material feature of my design consists in the configuration of a belt-body, in which one edge diverges from a central point toward the ends and the opposite edge is slightly concave or curved.

The letter A in the drawing indicates a belt-body which is wider at its central portion than at its ends, and one edge of the same from the central portion *a* extends toward the ends on diverging lines *a'*, which lead in an upward direction, as shown, and the opposite edge *b* is slightly curved or concave, the deepest portion of the curve being at the central portion of the belt-body.

I claim--

The design for a belt-body, substantially as shown and described.

JOSEPH ROSS.
